his Attorney

UNITED STATES PATENT OFFICE.

PIERRE PLANTINGA, OF CLEVELAND, OHIO.

RETORT.

1,239,517.

Specification of Letters Patent. Patented Sept. 11, 1917.

Application filed November 15, 1915. Serial No. 61,715.

To all whom it may concern:

Be it known that I, PIERRE PLANTINGA, a citizen of the United States, resident of Cleveland, county of Cuyahoga, and State 5 of Ohio, have invented a new and useful Improvement in Retorts, of which the following is a specification, the principle of the invention being herein explained and the invention being herein explained and the best mode in which I have contemplated applying 10 that principle, so as to distinguish it from other inventions.

My invention relates to coal stops for inclined gas retorts, its object being to provide a coal stop which may be readily operated 15 with a minimum of danger and inconvenience to the operator.

The said invention consists of means hereinafter fully described and particularly set forth in the claims.

20 The annexed drawing and the following description set forth in detail certain means embodying my invention, the disclosed means, however, constituting but one of various mechanical forms in which the principle 25 of the invention may be applied.

In said annexed drawing:—

Figure 1 represents a front elevation of a fragmentary portion of a retort embodying my invention, with the door removed.

30 Fig. 2 represents an axial vertical section of such fragmentary portion of a retort.

Fig. 3 represents a front elevation of a fragmentary portion of a retort embodying a modified form of my invention.

35 Fig. 4 represents a vertical axial section of a fragmentary portion of a retort embodying such modified form of my invention.

My invention as illustrated in Figs. 1 and 2, contemplates its application to an inclined 40 retort of a common construction in which the interior retort space is of the well-known and largely used cross-section. This well-known cross-section is one in which the base 45 of the cross-section is straight, the arch comparatively flat and the transverse dimension large as compared with the height. This type of retort, as used prior to my invention, contained this cross-section throughout its entire length and extended down to the outer 50 extremity, as indicated by the dotted lines *a* in Fig. 2.

In applying my invention to this type of retort, I cut away a portion of the upper and outer end of the masonry as at *b* so as to 55 increase the height of the discharge opening, as shown. A mouth-piece 1 is secured

in any approved manner to the outer vertical surface of the masonry and adjacent to the discharge opening of the retort space, and this mouthpiece is provided with an ordinary door 2. From the upper interior portion of the body of the mouth-piece and depending therefrom, are two integral lugs 3, 3, having an open bearing 4. In this bearing is seated a horizontal pivotal rod 5 which is 60 fixedly secured to a frame consisting of two angle bars 6, 6. These angle bars extend inwardly and downwardly from the pivotal axis and secured to their inner faces is the plate 7 intersecting the interior retort space 70 and intercepting the coal 8, holding same in the retort as required. As shown in the drawings, the dimensions of this plate 7 are such that it will, when in its normal or stopping position, have its lower end slightly removed 75 from the bottom or floor of the retort.

Suitably pivoted to the lower end of the frame is a brace 9 whose outer end is bent downwardly and provided with a nose 10 80 adapted to engage a notch 11 formed in the lower interior portion of the mouth-piece, as shown in Fig. 2. This brace is provided with a hole 12 into which the operator may insert a hook (not shown) secured to a 85 cable or chain passing over a trolley wheel suitably supported, by means of which he may lift the brace 9, disengage same from the notch 11 and thus permit the coal stop to swing outwardly and permit the coke 90 from the interior of the retort to be discharged as required, while he is standing at a safe distance and even to one side of the front of the retort. The lower end of the plate being out of contact with the floor of 95 the retort, it will be seen that the swinging of the stop is not resisted or impeded and its facility of operation is hence enhanced.

Where the retort to which my device is applied is of that type in which the cross-section of the retort space is such as illustrated in Figs. 3 and 4, in which the vertical dimension is considerably greater than the same dimension in the type of retort shown in Figs. 1 and 2, the cutting away of the 100 upper and outer portion of the masonry is unnecessary, inasmuch as such increased vertical dimension permits my improved type of device to be applied, as will be readily understood by those skilled in the 105 art.

It will be observed that by hanging or

pivoting the coal stop in the manner described, that is, at a point or in such a manner that it may be swung outwardly and at the same time away from the bottom 5 or floor of the oven, such bottom or floor is left clear and unobstructed and thus permits the coke to be most advantageously and readily discharged. Furthermore, by pivoting or hanging the stop to a fixed or 10 stationary part of the retort, the cover or door 2 may be removed or opened without disturbing the stop. This is an obvious advantage in that the door may be completely opened before the coke is permitted to discharge, thus allowing the discharge opening 15 covered by the door to be made absolutely free from obstruction before any of the coke is permitted to pass therethrough.

In this manner it will be observed that I 20 obtain an efficient and economical form of coal-stop which may be readily applied to any type of inclined retort at present in use.

It will be obvious to those skilled in the art that the above-described type of coal 25 stop may be advantageously applied to an inclined or horizontal coke oven. In the event that it is applied to a horizontal oven, however, it would be necessary to discharge the coke by means other than the force of 30 gravity, but the same advantages inhere, in so far as concerns making the stop independent of the door or cover and also in so far as they relate to keeping the floor or bottom free from obstruction.

35 Having fully described my invention, what I claim and desire to secure by Letters Patent is:—

1. The combination with a retort including 40 a mouth-piece; of a coal-stop mounted upon a stationary portion of the retort and adapted to swing outwardly and away from the floor thereof, whereby the coke may be discharged from beneath said stop.

2. The combination with a retort including 45 a mouth-piece; of a coal-stop mounted upon the body of the mouth-piece and adapted to swing outwardly and away from the floor of the retort, whereby the coke may be discharged from beneath said stop.

50 3. The combination of an inclined retort including a mouth-piece; a coal stop pivotally suspended from the body of such mouth-piece when said stop is in its normal or stopping position; and means for locking said stop in such suspended position.

4. The combination of an inclined retort including a mouth-piece; a coal stop pivotally suspended from the body of such 55 mouth-piece when in its normal or stopping position, said stop having a horizontal axis of oscillation; and means for locking the stop in such suspended position.

5. The combination of an inclined retort; 60 a coal-stop adapted to intersect the interior retort space; said stop being hung from a

stationary portion of the retort and adapted to swing outwardly and away from the floor of the retort; and means for holding said stop in place in said retort.

6. The combination of a retort; a coal 70 stop pivotally mounted upon a stationary portion of the retort and adjacent to its mouth, said stop being adapted to swing outwardly and away from the bottom of the retort floor; and means for locking said stop 75 in the retort whereby it may be made movable or stationary with respect to the retort walls.

7. In a retort construction, the combination 80 of an inclined retort; a coal-stop comprising a plate adapted to intersect the interior retort space, and a frame to which said plate is secured, said frame having an upwardly and outwardly extending portion pivotally secured to the retort and adjacent 85 to the mouth thereof; and means for holding said frame and plate in place in said retort.

8. In a retort construction, the combination 90 of an inclined retort including a mouth-piece; a coal-stop comprising a plate adapted to intersect the interior retort space, and a frame to which said plate is secured; said frame being pivotally mounted upon said mouth-piece; and means for holding said frame and plate in place in said retort. 95

9. In a retort construction, the combination 100 of an inclined retort including a mouth-piece; a coal-stop comprising a plate adapted to intersect the interior retort space, and a frame to which said plate is secured, said frame having an upwardly and outwardly extending portion pivotally secured to said mouth-piece; and means for holding said frame and plate in place in said retort.

10. In a retort construction, the combination 105 of an inclined retort; a coal-stop comprising a plate adapted to intersect the interior retort space, and a frame to which said plate is secured, said frame being pivotally mounted adjacent to the retort's 110 mouth; and a brace pivoted to said frame and extending outwardly therefrom; said retort being provided with means which may be detachably engaged by said brace, where- 115 by said frame and plate may be held in position in said space.

11. In a retort construction, the combination 120 of an inclined retort including a mouth-piece; a coal-stop comprising a plate adapted to intersect the interior retort space, and a frame to which said plate is secured, said frame having an upwardly and outwardly extending portion pivotally secured to said mouth-piece; and a brace pivotally secured to 125 said frame and extending outwardly from said frame; said mouth-piece being provided with a notch which may be engaged by the outer end of said brace, whereby said frame and mouth-piece are held in position in said space.

12. The combination of an inclined retort 130

including a mouth-piece; a coal stop pivotally mounted upon the body of such mouth-piece and having its lower end out of contact with the bottom or floor of the retort; and means for locking said stop in its stopping position.

13. The combination of an inclined retort; a coal stop pivotally suspended from a sta-

tionary portion of the retort and having its lower end out of contact with the bottom or floor of the latter; and means for locking said stop in its suspended stopping position.

Signed by me, this 1st day of October, 1915.

PIERRE PLANTINGA.
